Paracalle Naclerio

UNITED STATES PATENT OFFICE.

PASQUALE NACLERIO, OF WOODRIDGE, NEW JERSEY.

FABRIC-HOLDING DEVICE.

Application filed September 1, 1925. Serial No. 53,805.

One of the objects of my invention is to have the fabric or cloth, when spread upon a table beneath my device, securely held, irrespective of the number of plies of cloths 5 that may be under a portion of my holding device or any unevenness of the table.

With this and other objects in view which will appear as the description proceeds, the invention resides in the novel combination 10 and arrangement of parts hereinafter more particularly pointed out and claimed, it being understood that minor changes may be made within the scope of what is claimed without departing from the spirit or sacrificing any of the advantages of the invention.

Fig. 1 is a front elevation view of my device, shown upon a table.

Fig. 2 is a perspective view.
20 Fig. 3 is a top plan view.

Fig. 4 is a vertical section taken on line 4—4 of Fig. 3.

Fig. 5 is a longitudinal section taken on line 5—5 of Fig. 3.
25 Like reference numerals refer to like members in the various figures.

In Fig. 1 a table or board 1 is supported by the legs 2. Upon this table there are a number of plies of fabric 10 to be held securely against movement by the device. This device is composed of a series of preferably bell-shaped weights 3, having an integral stem member 4 extending upwardly and passing through the perforation 6 of 35 the flat elongated connecting bar, said bar and stem member forming a lost motion connection. This bar 7 is also graduated to form a rule. On the opposite end of the stem 4, screw threads are provided having 40 an adjustable nut 5 secured thereon. This device is also provided with a gripping handle 8 at the center of the connecting bar. 9 indicates a depression in the board and 10 indicates a fabric or cloth on the board.
45 The upper surface of the bar 7 is preferably graduated as shown at 11 whereby a rule or measurement device is formed. This

feature is convenient for measuring the width of the fabric.

Mode of operation.

When it is desired to hold plies of fabric securely to the table for cutting purposes, this device is elevated and placed upon the fabric. If there are more plies of fabric 55 on one portion of the table beneath this device than at another portion, it is obvious that the fabric will be securely held to the table throughout the entire length of my device, due to the weight of my device and 60 the lost motion connection between the elongated bar and bell-shaped weights, said weights thereby self adjusting to the various elevations on the table. It is also obvious that my device operates in the manner just 65 set forth due to any depression or unevenness that may be in the table or board.

Various changes may be made without departing from the spirit of the invention as 70 set forth and claimed.

Having thus described my invention what I claim as new and desire to secure Letters Patent upon is:

1. In a device of the class described, a series of bell-shaped weights each having an 75 integral member extending upwardly and passing through a flat elongated bar, said bell-shaped weights and bar forming a lost motion connection, said device supported by a base but entirely detachable from said 80 base, for the purpose described.

2. A fabric holding device, a series of 85 weights each loosely suspended by an integral stem passing through a flat elongated connecting bar, said weights and bar forming a lost motion connection, said device supported by a base but entirely detachable from said base, for the purpose described.

3. A fabric holding device, consisting of a flat, elongated bar having a gripping handle centrally located thereon, perforations in said bar, a series of bell-shaped weights loosely suspended by said bar, each of said weights having an integral stem ex-

tending upwardly and passing through said perforations in said bar thereby forming a lost motion connection between said bar and weights, said stem each being screw threaded at its upper extremity, an adjustable nut threaded on each of said stems, thereby adaptable to adjust the relative amount of lost motion that is desired in said device, and said weights thereby holding a fabric of unequal plies throughout the

entire length of said bar securely to a table or board due to said lost motion, said device supported by a base but entirely detachable from said base, for the purpose described.

In testimony whereof I have hereunto affixed my signature this 27th day of August, 1925.

PASQUALE NACLERIO.
